Primary Examiner — Holly Baynam*Assistant Examiner* — Rachel Voorhies(74) *Attorney, Agent, or Firm* — Senniger Powers LLP(57) **CLAIM**

The ornamental design for a sprinkler gun, as shown and described.

DESCRIPTION

FIG. 1 is a perspective view of a sprinkler gun showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

Portions of the sprinkler gun are shown in broken lines for illustrative purposes and form no part of the claimed design.
